US00D862445S

(12) **United States Design Patent** (10) Patent No.: **US D862,445 S**
(45) Date of Patent: ** Oct. 8, 2019

(54) **COVER FOR A MOBILE COMMUNICATIONS DEVICE**

(71) Applicant: **STMEC, LLC**, Poway, CA (US)

(72) Inventors: **Jeff Sasaki**, San Diego, CA (US); **Danny Yu**, San Bruno, CA (US)

(73) Assignee: **STMEC, LLC**, Poway, CA (US)

(**) Term: **15 Years**

(21) Appl. No.: **29/601,858**

(22) Filed: **Apr. 26, 2017**

(51) LOC (12) Cl. **14-03**

(52) U.S. Cl.

USPC **D14/250**

(57) **CLAIM**

The ornamental design for a cover for a mobile communications device, as shown and described.

DESCRIPTION

FIG. 1 is a front perspective view of a cover for a mobile communications device;

FIG. 2 is a front view of the cover for a mobile communications device of FIG. 1;

FIG. 3 is a rear view of the cover for a mobile communications device of FIG. 1;

FIG. 4 is a right side view of the cover for a mobile communications device of FIG. 1;

FIG. 5 is a left side view of the cover for a mobile communications device of FIG. 1;

FIG. 6 is a top view of the cover for a mobile communications device of FIG. 1; and,

FIG. 7 is a bottom view of the cover for a mobile communications device of FIG. 1.

The broken lines depict unclaimed portions of the cover for a mobile communications device.

1 Claim, 5 Drawing Sheets
